CAN PALLETIZING MACHINE

Marvin Bainbridge, Kahului, Territory of Hawaii, assignor to Maui Pineapple Company, Ltd., Honolulu, Territory of Hawaii, a corporation of Hawaii

Application June 8, 1953, Serial No. 360,059

8 Claims. (Cl. 198—34)

This invention relates to a can palletizing machine.

An object of this invention is to provide a machine wherein cans are arranged in a nested pattern thereby increasing the number of cans that may be stored on a pallet.

A further object of this invention is to provide a machine wherein cans are fed to the machine, arranged in a nested pattern, removed from the machine and positioned upon a pallet in a substantially continuous operation.

It is a further object of this invention to provide such a machine which will require a minimum of effort and operation on behalf of the operator.

Other objects and advantages will be readily apparent from the following description:

In the drawings:

Figure 1 is a side elevation of a can palletizing machine embodying this invention.

Figure 2 is a section taken along line 2—2 of Figure 1 illustrating the palletizing section of the machine.

Figure 3 is a top plan view of the can pattern forming section of the machine.

Figure 4 is a section taken along line 4—4 of Figure 1 illustrating the pattern removing portion of the machine with a portion thereof broken away.

Figure 5 is a section taken along line 5—5 of Figures 1 and 6 illustrating a pattern forming mechanism.

Figure 6 is a section taken along line 6—6 of Figure 5.

Figure 7 is a perspective view of the pattern forming mechanism adjustment bracket.

Figure 8 is a section taken along line 8—8 of Figure 4.

Figure 9 is a section taken along line 9—9 of Figure 4.

Figure 10 is a section taken along line 10—10 of Figure 9.

Figure 11 is a section taken along line 11—11 of Figure 4.

Figure 12 is a section taken along line 12—12 of Figure 4.

Figure 13 is a section taken along line 13—13 of Figure 12.

Figure 14 is a diagrammatic plan view of the pattern forming with the nested pattern forming stage full.

Figure 15 is a diagrammatic plan view of the pattern forming after a nested pattern has been removed from the forming stage.

Figure 16 is a diagrammatic plan view of the pattern forming during formation of a new nested pattern.

Referring now to the drawings and particularly Figure 1. The cans are delivered onto the pattern forming portion of the machine generally designated "A" from suitable conveyors "B."

Only the discharge end of the conveyors are illustrated as any form of conveyor may be utilized such as a moving belt delivering the cans in single file upright position. Two such discharges are illustrated although the number may of course vary.

As the cans are fed onto the pattern forming portion "A" they are advanced by a conveyor and a nested pat-

tern thereof is formed. This nested pattern is then delivered to a transfer mechanism "C." The transfer mechanism removes the nested pattern from the pattern forming portion "A" and delivers it to a pallet loading station "D." The nested pattern of cans is then placed upon the pallet and released. In this manner layer upon layer of cans are stacked with a sheet of paper between each layer, if desired, until the pallet is loaded to the desired amount. The pallet load of cans is then removed for storage.

As previously described, the conveyors "B" deliver the cans in single file in an upright position upon the conveyor 20 of the pattern forming section "A." The conveyor in this embodiment is the conventional flat top chain type although similar conveyors well known to those skilled in the art, may be substituted. Such conveyor should have a low coefficient of friction against the cans.

The upper surface of the conveyor is supported by suitable wear strips 21 which in turn are mounted upon channel members 23 mounted upon the side plates 32 and 34.

The conveyor chains form a horizontal surface and are looped over sprockets 22 and 24 at each end. The sprockets are mounted upon shafts 26 and 28 which shafts are rotatably supported between suitable bearings 30 at each extremity thereof. The bearings are mounted in side plates 32 and 34 of rectangular frame 36, which frame is supported by legs 38 above floor 40.

The motor 42 is suitably mounted on the frame and through reduction box 44 drives a sprocket 46. Trained around sprocket 46 is an endless chain 48, which is trained about sprocket 50 mounted upon shaft 26. Thus motor 42 through chain 48 drives shaft 26 and sprockets 22. The conveyor 20 is driven by sprockets 22 with sprockets 24 acting as idlers.

A chain tightening idler 51 may be provided to take up the slack in chain 48. Also, the idler sprockets 24 may be adjusted for the same purpose.

Thus as the cans are delivered by conveyors "B" onto the chain conveyor 20 they are advanced to the left in Figure 1.

The movement of the cans is interrupted during their progress to form a nested pattern of cans. This interruption is caused by pattern former 52. The pattern former in this embodiment is an angle iron having a plurality of pins 54 spaced along its lower surface. The pins are spaced from one another with center distances exactly equal to the width of the cans. When the pattern former 52 is in its lowered position the pins project a sufficient distance downwardly into the path of the cans arresting the progress of the cans.

The pattern former 52 is mounted at each extremity upon a shaft such as 56 by suitable nuts. The shaft 56 is supported for vertical movement in sleeve 58 mounted upon side plate 32 by means of bracket 60. Sleeve 58 is slotted as at 62 to receive block 64, which block is secured to shaft 56, and guides the vertical movement of the shaft.

The shaft 56 carries a cam follower 66 at its lower extremity which is in contact with double acting cam 68. The cam is mounted upon shaft 70 which is journaled in suitable bearings in side plates 32 and 34. The cam is formed of an inner segment 72 and an outer segment 74 which between them form a cam track so that as shaft 70 is rotated the cam follower 66 and hence pattern former 52 is raised and lowered. A suitable handle 76 is attached to shaft 70 to permit manual rotation thereof. The pattern former is lowered and the cans carried by conveyor 20 are stopped by pins 54 until a nested pattern of cans is formed. The cans form a line parallel to the pattern former 52 with a second line of cans also

parallel with the pattern former, but staggered with respect to the first line of cans, and so on, as seen in Figures 14, 15 and 16, thereby positioning a maximum number of cans within a given area. After the cans have filled the area between the pattern former 52 and the can arrester 78 the pattern former is raised and the can arrester lowered permitting the nested pattern of cans to be advanced by the conveyor.

The can arrester 78 is identical to the pattern former and hence, will not be described in detail. Each of the shaft 70 of the pattern forming mechanism and shaft 80 of the can arresting mechanism carries a sprocket such as 82. A chain 84 is trained over these sprockets and idler sprocket 85 so that if handle 76 on shaft 70 or a similar handle 86 on shaft 80 is rotated both shafts are rotated, rotating the cam 68 to raise or lower the pattern forming mechanism and the corresponding cam of the can arresting mechanism. The cams are formed so that when the pattern former 52 is raised the can arrester 78 is lowered and vice versa and the cams are also formed to insure that the can arrester 78 is completely lowered before the pattern former 52 is raised.

A stabilizing roller 88 is positioned behind the pattern former 52 with respect to the path of movement of the cans to prevent the cans raising or being injured when the pattern forming member is raised. This stabilizing roller is supported at each end by a bracket 90, which bracket is bolted to a second bracket 92 which in turn is bolted to a channel member 23. The bracket 90 has horizontal elongated holes 94 and 96 through which the bolts securing it to bracket 92 pass, thereby permitting horizontal movement of the roller with respect to the pattern former 52. The roller 88 is mounted upon a shaft 98 which projects through a vertical elongated slot 100 and into a block 102 and is secured therein by a pin 104. The block is mounted upon a bolt 106, the extremities of which project through slots 108 of bracket 90 and have nuts such as 110 screwed thereon. Thus by adjustment of the nuts the vertical position of the stabilizing roller is fixed.

A second stabilizing roller 112 is mounted directly behind the can arrester 78 in the same manner as roller 88 and for the same purpose.

Secured to bracket 92 is a side guard 114 which is also welded or otherwise secured to brackets 116 mounted on channel members 23. A side guard 114 is mounted upon each side of the machine to prevent cans falling off the conveyor 20 and at the end of the machine an end guard 118 is provided which terminates movement of the nested pattern of cans and positions the pattern below the transfer mechanism "C."

Mounted upon the frame of the pattern forming machine "A" are angle irons 120 which act as guides for the transfer mechanism. The transfer mechanism is mounted upon a conventional trolley track 122, and is raised or lowered by an electric hoist. In this embodiment a manifold of vacuum cups is illustrated although other means such as magnets, well known to those skilled in the art, may be substituted. Vacuum cups 124 are mounted in rows on suitable headers 126, which rows are staggered in the same manner as the cans in the nested pattern, with one vacuum cup for each can in the pattern.

A suitable vacuum source (not shown) is connected by a hose 128 to a three-way valve 130. The valve 130 is connected by a hose 132 to a three-way header cock 134. One such three-way header cock is provided for each header 126 and the cocks are joined by suitable pipes and with each header by means of a hose such as 136. The purpose of the cocks 134 is to enable the vacuum cup manifold to pick up any portion of a full layer by closing the cock immediately above the last full row of cans. This feature is often used at the end of a run or upon changing to a different pack item when a full layer is not available.

When the three-way valve is in one position the headers are communicated with the vacuum source and when in a second position are vented to the atmosphere.

Catch means are carried by the frame of the vacuum cup hoist to engage the angle iron guides 120 and thereby insure that the hoist is properly aligned with the nested pattern of cans. Catches 138 and 140 are urged outwardly by springs such as 142 and movably supported between down-turned extremities of a bracket such as 144. The catches are positioned by links 150 and 152 to each extremity of lever 154, so that as lever 154 is rotated the catches are moved inwardly or outwardly. The lever 154 is positioned by means of handle 156 which is pivoted about shaft 158 which synchronizes the action of the catches with the operation of the three-way vacuum control valve 130. The lever 154 is connected by links 160 and 162 to shaft 164 upon which the lever 154 is mounted. Thus when the vacuum cup transfer mechanism is lowered by actuating the electric hoist through switch 166, the angle iron guides 120 are projected into a suitable space in the frame and handle 156 is rotated to move spring catches 138 and 140 to the outer position to engage angle iron guides 120 and insure that cups 124 are lowered in the proper relationship with respect to the nested pattern of cans. As the handle 156 is rotated in the opposite direction it actuates valve 130 to communicate the vacuum source with the cups 124 and simultaneously depresses the spring catches 138 and 140 and causes spring catches 138A and 140A to protrude for cooperation with angle iron guides 120A.

The headers 126 are secured by suitable brackets 170 to a rectangular frame 172. The frame 172 is held on the hoist frame 174 by bolts 176 which pass through frame 172 and are screwed into frame 174. Suitable springs 178 urge the frame 172 and headers 126 downwardly while permitting them to raise relative to the hoist frame 174. In this manner the cans which are upon the pattern forming conveyor 20 are not injured upon contact with vacuum cups 124. Each vacuum cup grasps a can in the pattern and the electric hoist switch 166 is actuated to raise the transfer mechanism "C."

At the upper position of the transfer mechanism it is caused to move to the left in Fig. 1, either as a free rolling trolley or a powered trolley if desired. The switch 166 is again actuated to lower the transfer mechanism. A pair of catches corresponding to catches 138 and 140 on the rear side of the transfer mechanism engage suitable guides 180 at the end of track 122. The switch 166 is actuated to lower the transfer mechanism.

The layer of nested cans carried by the conveyor are thus lowered onto the preceding layer and valve 130 actuated to vent the vacuum cups 124 to the atmosphere, releasing the cans. The hoist is again raised and returned to pick up the next nested pattern of cans formed in the pattern forming mechanism "A" between the pattern former 52 and can arrester 78 and then released to move to a position beneath the transfer mechanism.

Between each successive layer of cans a sheet of paper 60 may be positioned to bind the layers together. The layers are supported upon a pallet 181. When a pallet has sufficient layers of cans a hydraulic ram 182 is actuated to move the loaded pallet from under the transfer mechanism and replace it with an empty pallet.

In operation cans are fed to the continuously moving conveyor 20 in one or more lanes with the pattern former 52 lowered and can arrester 78 raised. The cans then fill the space between the pattern former and can arrester in a nested relationship. The can arrester is lowered 70 and then the pattern former is raised and the nested pattern or layer of cans is advanced to a position below the transfer mechanism "C." This mechanism is lowered onto the cans and the valve 130 actuated to communicate the vacuum cups 124 with the vacuum source. The nested pattern of cans is raised upon raising of the trans-

fer mechanism and transferred to the pallet 181 and released.

While what hereinbefore has been described is the preferred embodiment of this invention it is readily apparent that alterations and modifications can be resorted to without departing from the scope of this invention and such alterations and modifications are intended to be included within the scope of the following claims.

I claim:

1. A can palletizing machine comprising: a continuous conveyor upon which cans can be moved in any direction free from impediment and which comprises the sole moving force for such cans, stop means including a plurality of pins spaced from one another a distance less than the width of such cans positioned above said conveyor and means successively feeding cans onto said conveyor which cans are carried against said pins and formed into a nested pattern of cans.

2. A can palletizing machine comprising: a continuous conveyor upon which cans can be moved in any direction free from impediment and which comprises the sole moving force for such cans, a side guard adjacent each side of said conveyor, stop means including a plurality of pins spaced from one another a distance less than the width of such cans positioned above said conveyor and means successively feeding cans onto said conveyor which cans are carried against said pins and formed into a nested pattern of cans.

3. A can palletizing machine comprising: a continuous conveyor upon which cans can be moved in any direction free from impediment and which comprises the sole moving force for such cans, a side guard adjacent each side of said conveyor, primary stop means including a plurality of pins spaced apart less than the width of such cans, means feeding cans successively onto said conveyor, which cans are carried against said primary stop means and form a nested pattern between said side guards, secondary stop means positioned between said primary stop means and said feed means movable into position to prevent movement of cans to said primary stop means and said primary stop means being movable to permit the accumulated nested pattern of cans to pass beyond said primary stop means.

4. A can palletizing machine comprising: a continuous conveyor upon which cans can be moved in any direction free from impediment and which comprises the sole moving force for such cans, a side guard adjacent each side of said conveyor, adjustable primary stop means including a plurality of pins spaced from one another less than the width of such cans, means feeding cans successively onto said conveyor which cans are carried against said primary stop means, adjustable secondary stop means positioned between said primary stop means and said feed means, means controlling the vertical position of both primary and secondary stop means so that when the secondary stop means are raised cans are stopped by said primary stop means and form a nested pattern between said side guards and said primary and

secondary stop means, and when said control means lowers said secondary stop means to interrupt flow of cans said primary stop means are raised to permit the accumulated nested pattern of cans to advance on said conveyor.

5. A can palletizing machine comprising: a continuous conveyor upon which cans can be moved in any direction free from impediment and which comprises the sole moving force for such cans, means feeding cans onto said conveyor, vertically adjustable primary stop means including a plurality of pins spaced apart a distance less than the width of such cans, vertically adjustable secondary stop means between said feed means and said primary stop means, control means for said stops raising said secondary stop means and lowering said primary stop means so that cans engage said pins and fill said conveyor between said stop means in a nested pattern, said control means lowering said secondary stop means interrupting flow of cans on said conveyor and raising said primary stop means permitting the pattern of nested cans accumulated to advance on said conveyor.

6. The combination set forth in claim 5, wherein means are provided to permit said secondary stop means to be completely lowered before said primary stop means are raised.

7. A can palletizing machine comprising: a continuous can carrying conveyor upon which cans may be moved in any direction free from impediment and which comprises the sole moving force for such cans, a pair of pattern forming stop means each having a plurality of pins spaced apart a distance less than the width of said cans upon said conveyor positioned above said conveyor and means to alternately raise and lower said pattern forming stop means so that the cans will engage said pins to form and release a nested pattern of cans.

8. A can palletizing machine comprising: a continuous can carrying conveyor upon which cans may be moved in any direction free from impediment and which comprises the sole moving force for such cans, a pair of pattern forming stop members each having a plurality of pins thereon positioned above said conveyor said pins being spaced from one another a distance less than the width of said cans on said conveyor, means to alternately raise and lower said pattern forming stop members so that cans on said members will engage said pins to form a nested pattern of can and means delaying the raising of the stop member furthest from the source of supply of cans until the other stop member has been lowered.
